(57) **CLAIM**

The novel ornamental design for a rectangular vented light-emitting diode light with rotating base, as shown and described.

DESCRIPTION

FIG. 1 is a perspective view of the rectangular vented light-emitting diode light with rotating base;

FIG. 2 is a front elevational view of the rectangular vented light-emitting diode light with rotating base in accordance with the present invention;

FIG. 3 is a right side view of the rectangular vented light-emitting diode light with rotating base;

FIG. 4 is a left side view of the rectangular vented light-emitting diode light with rotating base;

FIG. 5 is a top view of the rectangular vented light-emitting diode light with rotating base;

FIG. 6 is a bottom view of the rectangular vented light-emitting diode light with rotating base;

FIG. 7 is a back elevational view of the rectangular vented light-emitting diode light with rotating base; and,

FIG. 8 is a front elevational view of the rectangular vented light-emitting diode light with rotating base showing a typical base (not claimed) that can be fitted to the rotational base; and,

FIG. 9 is a front elevational view of the rectangular vented light-emitting diode light with rotating base showing another typical base (not Claimed) that can be fitted to the rotational base thereon.

The broken lines in the drawings represent unclaimed environmental subject matter.
